SCREW-ACTUATED JAW TYPE WRENCH

Alfred R. Oberwegner, Los Angeles, Calif.

Application June 28, 1952, Serial No. 296,141

7 Claims. (Cl. 81—163)

1

This invention relates generally to the tool art and is concerned more particularly with a combined wrench and puller tool for use in servicing clothes washing machines.

Conventional clothes washing machines include a center post which extends upwardly above the bottom of the tub, a vertical oscillatable shaft extending through the post and having an upper projecting end to which the clothes agitator is keyed for oscillation therewith. In some washing machines, the post has a lower screw-threaded end which passes through a hole in the tub and is screwed into a hole in the housing of the driving mechanism, the post usually having a nut-like portion by which it can be screwed into and from the housing. In other machines, the center post is held in place by means of a large nut-like collar which is screwed onto a threaded portion of the post and against the top surface of the tub bottom. In either case, it is extremely difficult to remove the center posts for the reason that the interengaging threads of the post and associated parts become corroded and considerable torque is required to rotate the elements to unscrew the same. Various types of wrenches have been proposed for gripping the part to be screwed into or from the washer, one such wrench being disclosed in my patent for Adjustable Socket Wrench, No. 2,443,774, issued June 22, 1948. While such a wrench is quite effective in unscrewing certain types of post nuts, even when the nuts are tightly corroded in place, it is not adapted to remove all the various types of nuts currently employed in washers of the many different makes. In addition, in such prior jaw-type wrenches, the jaws are adjusted toward and away from each other by means located adjacent the lower end of the tool, within the tub, and it is thus extremely difficult to effect adjustment of the jaws. Moreover, since the tool must be retained in upright position by one hand, as the jaws are adjusted by the other hand, it is apparent that the procedure of setting up the tool for use is a rather laborious one which consumes valuable time and thus increases the costs involved in repairing the washing machine.

It is an important object of this invention to obviate the faults and deficiencies of such prior washing machine wrenches by providing a wrench, of the jaw type, which is highly practical and efficient, and one which is universal in use, being capable of operating on all types of center posts and center post nuts employed in all current clothes washing machines.

Another object of the invention is to provide

5 a wrench, of the character referred to, having a pair of relatively slidable jaws for gripping the machine part to be tightened or loosened, and actuating means operatively connected to the jaws for actuating the latter to grip or release the part, said actuating means extending upwardly to a position above the washing machine tub so as to be accessible for manual operation.

10 Another object is to provide in a wrench of the type indicated manually operable means for pivoting the jaw levers to operative and inoperative positions, this operating means consisting of an operating screw which is screwed through nuts pivotally mounted at the upper free ends of the jaw levers. In accordance with the present concept, the operating screw has screw threads of opposite pitch engageable in correspondingly threaded holes of the nuts. By this arrangement, 15 rotation of the operating screw in one direction causes the jaw levers to move in a direction to close the gripping jaws and rotation of the screw in the other direction acts to pivot the levers in the opposite direction to open the jaws. In addition, by employing such an operating screw, its threaded portions of opposite hand function in the manner of a double thread so that the wrench is rendered quick-acting with the result that the jaws may be quickly opened and closed as required. Moreover, through this particular arrangement of elements the mechanical advantage is increased so that the jaws may be firmly clamped against an object with a minimum of physical exertion on the part of the mechanic servicing the machine. As an added feature, 20 manipulation of the jaws is accomplished entirely from outside the washing machine tub so that it is unnecessary to reach down into the tub to adjust the jaws to the object being turned. Moreover, the wrench may be conveniently rotated by 25 grasping the opposite ends of the relatively long operating screw in the hands to produce the torque necessary to loosen badly corroded parts and unscrew them from the machine.

25 Another object is to provide a wrench of this type in which the jaw levers carry inwardly directed, adjustable stop screws, the inner ends of which are adapted to engage against the center-post of the washing machine to retain the wrench in upright position during its operation. This is an important improvement over prior wrenches 30 designed for the same purpose but which may tilt relative to the part being loosened to cause insecure gripping action of the jaws.

35 Further objects will appear from the following

description and from the drawings, which are for the purpose of illustration only, and in which:

Fig. 1 is a perspective view of the upper portion of a conventional clothes washing machine, showing my improved wrench, including its puller attachment, as applied to use in removing the spinner tub of the machine;

Fig. 2 is a side elevational view of the combined wrench and puller device, partly in section;

Fig. 3 is a sectional plan view, taken on line 3—3 of Fig. 2;

Fig. 4 is an enlarged fragmentary view as observed in the direction of arrow 4 in Fig. 2;

Fig. 5 is a perspective view of the bottom of the jaws;

Figs. 6, 7 and 8 are enlarged bottom views of the jaws, showing them applied to use in gripping nut-like elements of various forms;

Fig. 9 is a cross-sectional view through the lower portion of the device, showing its impact means applied to use;

Fig. 10 is a side view of the jaws showing them applied to use in a washer having a recessed portion in the tub; and

Fig. 11 is an enlarged fragmentary view of the thread-cutting portion of one of the jaws, taken on line 11—11 of Fig. 8.

Referring to the drawings in detail, my improved washing machine wrench includes a substantially rectangular jaw plate 15 to the lateral edges of which are secured by any means, such as welding, a pair of elongate guide elements 16 having longitudinal guideways 17. A cross-bar 18 is welded between the free ends of the elements 16 to provide a rigid, rectangular jaw frame of which the jaw plate 15 is an integral part. A second jaw plate 20 has its lateral edges disposed in said guideways 17 to adapt this plate to slide in the frame toward and away from the jaw plate 15.

The jaw plates 15 and 20 have respective transversely spaced, upstanding ears 21 and 22 between which extend pivot pins 23 and 24. Pivot on the pins 23 and 24 are upstanding jaw levers 25 and 26, the upper ends of which diverge slightly. Intermediate their ends, the levers 25 and 26 are provided with respective pairs of arms 27 and 28, pivot studs 29 extending through holes in these arms to pivotally connect the jaw levers. As shown in Fig. 3, the studs 29 are extended inwardly. The jaw levers 25 and 26, which are of channel-shaped cross section, carry stop screws 30 for the purpose to be later explained.

The upper ends of the jaw levers 25 and 26 are bifurcated and extending transversely through the sides of these forked ends are pivot screws 33 upon which are pivoted nut elements 34 provided with aligned bores 35 having screw threads of opposite hand. Threaded through said bores is an operating screw 38 which has a central screw-threaded portion and plain tubular end sections 39. The central portion is composed of two threaded tubular sections 40 and 41 which, as illustrated, have external screw threads of opposite hand to adapt them to be screwed through the bores 35 of the nut elements 34. As shown in Fig. 2, the inner abutting ends of the threaded tubular sections 40 and 41 are connected by a cylindrical plug 42 inserted in said ends and by welding 43. The outer end sections 39 are joined to reduced outer portions of the center sections 40 and 41 by means of pieces 43'. One of the end sections 39 has a transverse hole through which extends a rod 44 by which the operating screw 38 can be manually rotated.

It will be apparent from the foregoing description that rotation of the screw 38 in one direction in the nut elements 34 will cause the upper ends of the jaw levers 25 and 26 to move apart and, due to the intermediate pivots 29, the lower ends of the levers will move inwardly toward each other, and rotation of the screw in the opposite direction will cause the lower ends of the levers to move apart. In this manner, the jaw plates 15 and 20 are caused to move toward and away from each other, for the purpose to be hereinafter explained. As will be apparent to one versed in mechanics, the opposite hand threads of the sections 40 and 41 act in the manner of a double pitch thread arrangement so that the jaw levers are pivoted through a considerable angle during each rotation of the operating screw. The operating means thus may be regarded as quick-acting.

Detachably connected to the under sides of the jaw plates 15 and 20 by screws 49 are jaw elements 50 and 51 of generally arcuate shape, the lower surfaces of these elements extending below the guide elements 16, as shown in Figs. 4 and 10, for the purpose to be later explained. The facing edges of the jaw elements 50 and 51 have arcuate recesses 52 which are provided with screw threads 53 of the form illustrated in Fig. 11, the threads of the two elements together providing a continuous helix when the elements are moved to a position where the recesses 52 form concentric parts of a complete circle. At the ends of the arcuate recesses 52, the jaw elements 50 and 51 have cut-outs 55 provided with curved portions 56. The recesses 52 also have curved grooves 57 at their centers and V-shaped notches 58 at the sides of the grooves 57.

By this particular arrangement of the recesses 52, cut-outs 55, 56, grooves 57 and notches 58, the irregularly shaped space between the jaw elements 50 and 51 provides a wrench socket adapted to receive various types of nut-like elements which surround or form part of the center-posts of the washing machines. For example, the jaw elements 50 and 51 are adapted to receive between them a nut 60 of the type shown in Fig. 6, said nut having opposite wing-like projections 61 engageable in the curved portions 56. A cylindrical nut element 62 (Fig. 7) may be gripped between the jaw elements, opposite lugs 63 of the element fitting in the central grooves 57. The jaw elements also may receive a nut element 64 of the type illustrated in Fig. 8, the V-shaped notches 58 receiving pointed projections 59 of the element. Thus, by the particular shape of the socket formed by the jaw elements, a large variety of nuts and nut-like portions of center-posts may be firmly gripped between the jaw elements and keyed against rotation relative to these elements so that when the parts are clamped between the jaws and the entire tool rotated, the parts of the washing machines are positively rotated. Some washers employ a sheet metal guard 70 (Fig. 10) over the drain opening 71 of the tub. The present wrench tool is adapted to remove a nut 72 when the latter is located in such a tub, it being observed that the height or thickness of the jaw elements 50 and 51 is sufficient to adapt the jaw frame 15, 20, 16 to rotate in a plane above the guard 70 to clear the same.

It frequently occurs that a center-post or the nut thereon is so tightly frozen in place that it must be struck tangential blows to break the corrosion before it can be turned by conventional

centerpost wrenches. It has been determined that the torque produced by my wrench is usually sufficient to loosen very tightly frozen parts. However, to guard against a situation where the part may be extremely difficult to dislodge, I provide a striker means 15 as shown in Fig. 9. This means consists of a relatively long bolt 16 having a threaded end adapted to be screwed selectively into either of two inclined bosses 17 or 18 provided at an end of the guide elements 16, a check-nut 19 on the bolt being set up against the boss to retain the bolt in place. A relatively heavy striker block 20 is slidably axially on the bolt 16. With the bolt secured in place in the boss 17 and the jaw elements tightly engaging the nut or other part to be loosened, the striker block is reciprocated on the bolt to cause it to intermittently strike the nut 19 and boss 17 with sufficient impact force to break the corrosion and jar the nut loose so that upon rotation of the wrench device in counterclockwise direction, the nut will be unscrewed from the post. Conversely, the nut may be screwed onto the post and set up tightly by screwing the bolt 16 into the other boss 18 and then operating the striker or impact weight 20 to hammer the wrench around in clockwise direction.

As thus far described, my improved washing machine tool is adapted for use in tightening and loosening nuts and center-posts by rotating the same. Some washing machines have spinner baskets which must be removed for servicing or repair. Such a spinner basket is usually supported on a long tubular member, such as shown at 35 in Figs. 1 and 2, the member being carried by a tapered driving shaft 86. Due to the tapered driving connection between these parts, it is extremely difficult to loosen the member from the shaft. Various devices have been proposed for this purpose but these are inefficient for different reasons, the most important of which is that the puller tool frequently slips out of place to release or damage the support member.

In order to make my wrench tool universal in use, so that it can remove such support members as well as loosen nuts and other threaded elements, I provide a puller attachment 90 which can be utilized only in conjunction with the wrench. Referring to Figs. 1 and 2, the puller 90 comprises an H-shaped frame 91 having opposite side beams 92 connected by a central cross-bar 93, these parts being preferably made from structural shapes. The frame 91 is adapted to be positioned on the wrench with its beams 92 disposed against the sides of the jaw levers 25 and 26 and with its cross-bar 93 extending transversely through the space occurring between said levers. When in this operative position, the beams engage against abutment pins 95 carried by and projecting laterally from opposite sides of the jaw levers. The cross-bar 93 has a vertical threaded hole through which is screwed a pusher bolt 96, the lower end of which seats within a socket 97 formed in a plug 98, the latter having a reduced end received in the upper end of a pusher tube 99 which is inserted into the upper end of the basket support member 85 with its lower end engaging the upper end of the driving shaft 86.

To pull the support member 85 upwardly from the tapered shaft 86, the wrench device is placed over the member as shown in Figs. 1 and 2 and by rotating the operating screw 38 the jaw elements 50 and 51 are drawn toward each other to grip the lower portion of the support member there-

between. By simultaneously rotating or oscillating the wrench and operating the screw 38, the screw-threaded portions 53 of the jaw elements 50 and 51 are caused to cut a screw thread in the periphery of the support member, as shown in Fig. 2. The wrench is thus positively engaged with the support member to prevent relative axial movement therebetween.

The pusher tube 99 is next inserted into the upper end of the support member 85 to cause its lower end to rest against the upper end of the shaft 86. The H-shaped frame 91 is then placed on the jaw levers 25, 26 as shown, after which the pusher bolt 96 is screwed downwardly into the socket 97 of the tube 99. It is to be noted that the stop screws 30 and the pivot studs 29 serve to center the wrench with respect to the support member (Figs. 2 and 3).

By rotating the pusher bolt 96 clockwise, the bolt and the tube 99 are forced downwardly against the shaft 86. Now, since the jaw elements 50 and 51 are locked to the support member 85 by reason of their interengaging screw threads, it follows that continued manipulation of the bolt 96 must result in upward sliding movement of the support member 85 to cause it to be stripped from the shaft 86. By lifting the entire device from the washer, the support member 85 is removed from its shaft, after which the pusher means is disassembled and the jaws opened to free the member.

In accordance with the provisions of the patent statutes, I have described the principle of operation of my invention, together with the device which I now consider to represent the best embodiment thereof, but I desire to have it understood that the device shown is only illustrative and that the invention may be carried out by modified means.

I claim as my invention:

1. A device of the class described, comprising: a jaw frame; a first jaw element fixedly secured to said frame at one end thereof; a second jaw element slidably on said frame toward and away from said first jaw element; a first upright jaw lever pivoted to said frame above said first jaw element; a second upright jaw lever pivotally connected to said second jaw element, said jaw levers being pivotally connected intermediate their upper and lower ends and adapted when their lower ends are pivoted toward each other to close said jaw elements to adapt the latter to grip an object therebetween, said jaw elements having facing, concave, object-gripping, edge portions provided with notches therein adapted to receive projections of the object to key the object and jaw elements against relative rotation; nuts pivotally mounted at the upper ends of the jaw levers, said nuts having axially aligned bores provided with screw threads of opposite hand; and an operating screw having two coaxial portions provided with screw threads of opposite hand and rotatable in said nuts, rotation of said operating screw in opposite directions acting through said nuts and said jaw levers to move said jaw elements toward and away from each other to grip and release the object, said operating screw having an axial extension providing a handle by which the device and the object gripped thereby can be rotated.

2. A device of the class described, comprising: a jaw frame having longitudinal guideways; a first jaw element fixedly secured to said frame at one end thereof; a second jaw element slidable in said guideways toward and away from said

first jaw element; a first upright jaw lever pivoted to said frame above said first jaw element; a second upright jaw lever pivotally connected to said second jaw element, said jaw levers being pivotally connected intermediate their upper and lower ends and adapted when their lower ends are pivoted toward each other to close said jaw elements to adapt the latter to grip an object therebetween, said jaw elements having facing, concave, object-gripping edge portions provided with notches therein adapted to receive projections of the object to key the object and jaw elements against relative rotation; nuts pivotally mounted at the upper ends of the jaw levers, said nuts having axially aligned bores provided with screw threads of opposite hand; and an operating screw having two coaxial portions provided with screw threads of opposite hand and rotatable in said nuts, rotation of said operating screw in opposite directions acting through said nuts and said jaw levers to move said jaw elements toward and away from each other to grip and release the object, said operating screw having an axial extension providing a handle by which the device and the object gripped thereby can be rotated.

3. A device of the class described, comprising: a jaw frame; a first fixed jaw plate integral with said frame; a first jaw element secured against the bottom of said first jaw plate; a second jaw plate slidable on said frame toward and away from said first jaw plate; a second jaw element secured against the bottom of said second jaw plate; a first upright jaw lever pivoted to said first plate; a second upright jaw lever pivoted to said second plate, said jaw levers being pivotally connected intermediate their upper and lower ends and adapted when their lower ends are pivoted toward each other to close said plates and the jaw elements secured thereto to adapt the jaw elements to grip an object therebetween, said jaw elements having facing, concave, object-gripping, edge portions provided with notches therein adapted to receive projections of the object to key the object and jaw elements against relative rotation; nuts pivotally mounted at the upper ends of the jaw levers, said nuts having axially aligned bores provided with screw threads of opposite hand; and an operating screw having two coaxial portions provided with screw threads of opposite hand and rotatable in said nuts, rotation of said operating screw in opposite directions acting through said nuts and said jaw levers to move said jaw elements toward and away from each other to grip and release the object, said operating screw having an axial extension providing a handle by which the device and the object gripped thereby can be rotated.

4. A device of the class described, comprising: a jaw frame; a first fixed jaw plate integral with said frame; a first jaw element secured against the bottom of said first jaw plate; a second jaw plate slidable on said frame toward and away from said first jaw plate; a second jaw element secured against the bottom of said second jaw plate; a first upright jaw lever pivoted to said first plate; a second upright jaw lever pivoted to said second plate, said jaw levers being pivotally connected intermediate their upper and lower ends and adapted when their lower ends are pivoted toward each other to close said plates and the jaw elements secured thereto to adapt the jaw elements to grip an object therebetween, said jaw elements having

facing, concave, object-gripping, edge portions provided with notches therein adapted to receive projections of the object to key the object and jaw elements against relative rotation; nuts pivotally mounted at the upper ends of the jaw levers, said nuts having axially aligned bores provided with screw threads of opposite hand; and an operating screw having two coaxial portions provided with screw threads of opposite hand and rotatable in said nuts, rotation of said operating screw in opposite directions acting through said nuts and said jaw levers to move said jaw elements toward and away from each other to grip and release the object, said operating screw having an axial extension providing a handle by which the device and the object gripped thereby can be rotated; and screws on said jaw levers engageable with the object to center the device relative thereto.

5. A device of the class described, comprising: a jaw frame; a first fixed jaw plate integral with said frame; a first jaw element secured against the bottom of said first jaw plate; a second jaw plate slidable on said frame toward and away from said first jaw plate; a second jaw element secured against the bottom of said second jaw plate; a first upright jaw lever pivoted to said first plate; a second upright jaw lever pivoted to said second plate, said jaw levers being pivotally connected intermediate their upper and lower ends and adapted when their lower ends are pivoted toward each other to close said plates and the jaw elements secured thereto to adapt the jaw elements to grip an object therebetween, said jaw elements having facing, concave, object-gripping, edge portions provided with notches therein adapted to receive projections of the object to key the object and jaw elements against relative rotation; nuts pivotally mounted at the upper ends of the jaw levers, said nuts having axially aligned bores provided with screw threads of opposite hand; and an operating screw having two coaxial portions provided with screw threads of opposite hand and rotatable in said nuts, rotation of said operating screw in opposite directions acting through said nuts and said jaw levers to move said jaw elements toward and away from each other to grip and release the object, said operating screw having an axial extension providing a handle by which the device and the object gripped thereby can be rotated; and screws on said jaw levers engageable with the object to center the device relative thereto, said concave edge portions of said jaw elements having portions of screw threads thereon cooperating, when the jaw elements are urged toward each other and the device rotated, to cut a screw thread in the periphery of the object.

6. In a wrench device of the type having a pair of jaw levers pivotally connected intermediate their ends, jaw elements pivotally carried by corresponding ends of the levers and adapted, when said ends are moved together, to grip an object therebetween, and screw means operatively connected between the opposite ends of the jaw levers and adapted, when rotated in opposite directions, to move said jaw elements toward and away from each other; a jaw frame carried by and movable with one of said jaw elements and having grooves extending in the direction of movement of the jaw elements, said grooves together providing a guideway, lateral edges of the other jaw element being slidable in

said grooves to guide said jaw elements in their movement toward and away from each other.

7. In a wrench device of the type having a pair of jaw levers pivotally connected intermediate their ends, jaw elements pivotally carried by corresponding ends of the levers and adapted, when said ends are moved together, to grip an object therebetween, and screw means operatively connected between the opposite ends of the jaw levers and adapted, when rotated in opposite directions, to move said jaw elements toward and away from each other; a U-shaped jaw frame having spaced, parallel longitudinal elements fixedly connected to the side edges of one jaw element and a cross-bar extending between said longitudinal elements remotely from said one jaw element, said longitudinal elements having grooves therein, the other jaw element having side edges slidable in said grooves to guide it during its movement toward and away from said one jaw element, said cross-bar providing a stop for engagement by said other jaw element to limit its sliding movement away from said one jaw element.
